JOSEPH E. GARIGLIO, OF BROOKLYN, NEW YORK.

SAFETY ATTACHMENT FOR WASHING MACHINES.

Application filed August 15, 1925. Serial No. 50,423.

This invention relates to washing machines and has particular reference to a safety attachment therefor.

The principal object of the present invention is to provide an improved attachment for a power washing machine, means for rendering the machine inoperative except when the doors of the outer casing are closed.

More specifically, the invention contemplates an improved safety attachment for washing machines, which includes means for locking the outer casing doors in a closed condition, which means is operatively connected with the driving mechanism of the machine so that when the locking means is released the driving mechanism is rendered inactive.

The invention furthermore comprehends a washing machine door-locking device having operative connection with the inner cylinder-driving mechanism for simultaneously rendering said mechanism inactive when the locking means is released and for rendering the driving mechanism active when the lock mechanism is in locking relation to the door.

The invention still further comprehends a safety attachment of the character set forth, which is comparatively simple in its construction and mode of operation, which is inexpensive to manufacture and install, and which is thoroughly reliable and highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a fragmentary front view of a washing machine equipped with a safety door constructed in accordance with the invention;

Fig. 2 is an enlarged sectional view therethrough taken approximately on the line indicated at 2—2 in Fig. 1;

Fig. 3 is a fragmentary similar sectional

view illustrating the locking mechanism released for rendering the driving mechanism inactive;

Fig. 4 is a fragmentary sectional view taken approximately on the line 4—4 of Fig. 2;

Fig. 5 is a sectional view taken approximately on the line 5—5 of Fig. 4;

Fig. 6 is a similar sectional view taken approximately on the line 6—6 of Fig. 4;

Fig. 7 is a fragmentary sectional plan view taken approximately on the line 7—7 of Fig. 1;

Fig. 8 is a fragmentary detail side view;

Fig. 9 is a fragmentary horizontal sectional view taken approximately on the line 9—9 of Fig. 2.

Referring to the drawings by characters of reference, 10 designates the substantially cylindrical outer casing or housing of the machine, within which the drums or barrels 11 containing the articles to be laundered are rotated alternately in opposite directions in the usual manner. The drums or barrels 11 have hinged sections 12 which when opened afford a doorway for inserting or removing the articles to be washed. The outer casing or housing 10 is likewise provided with an opening or doorway 13 which is closed by means of a sliding door or closure 14 mounted in guideways 15. The doors or closures 14 are provided with window openings 16 closed by closures 17, by means of which the operator may observe the position of the inner barrels or drums when stopping the machine, so that the hinged sections will register or coincide with the opening or doorway 13 of the outer casing or housing.

The inner drums or barrels 11 are secured to an axially extending shaft 18 having secured to its opposite externally disposed extremities, gears 19 with which gears 20 of a reducing train mesh, which gears 20 in turn mesh with pinions 21. The pinions 21 are secured to the opposite ends of a shaft 22 upon which a pulley 23 is keyed. Loosely mounted on the shaft 22 on opposite sides of the tight pulley 23, are loose pulleys 24 and 25, each respectively driven by belts 26 and 27 from a common drive pulley (not shown) on a power shaft. The belt 26 is crossed whereby the loose pulley 24 is driven in an opposite direction from the loose

pulley 25. The loose pulley 25 has secured thereto a worm 28 which meshes with a worm gear 29 having an eccentric pin 30 operable in a cam opening 31 in a rock arm 32. The rock arm 32 is provided with an arcuate head 33 having a central notch 34. A slide rod 35 is connected with a carriage 36 which in turn is operatively connected with the belt shifting loops 37 and 38. A coupling bolt 39 having a weighted head 39a is secured to and extends radially from the slide rod, which slide rod is turnable or swivelly connected with the carriage 36, whereby the coupling bolt may be swung into and out of engagement with the notch 34 of the head 33 of the rock arm. When engaged within the notch, the coupling bolt connects the slide rod with the rock arm so that the carriage is reciprocated to alternately shift the belts 26 and 27 into active engagement with the tight pulley 23 for driving the shaft 22 alternately in opposite directions and for consequently reversing the motion of the drums or barrels 11. At the present time machines of this type are thrown into and out of operation by swinging the coupling bolt 39 into and out of engagement with the notch independently of the opening and closing of the closure or door 14, so that it is obvious that a workman may be injured by starting the machine with his arms or other parts of his person disposed within the open doorway 13. Furthermore, in many instances, machines have been started with the door 12 open and extending through the opening or doorway 13 of the outer casing, thereby causing considerable damage.

The present invention constituting an attachment for the machine, consists of a locking means in the nature of a pair of spring-pressed bolts 40 mounted for vertical sliding movement in the apertured cross arms 41 of a standard 42, which is secured to and projects upwardly from the center of the outer casing or housing 10. The bolts have secured thereto collars 43 between which and the lower cross arm 41, coil expansion springs 44 are interposed for normally effecting upward sliding movement of the bolts away from the outer surfaces of the sliding closures 14. The sliding closures 14 are in turn provided with keeper openings 45, through which the bolts 40 are adapted to be shot against the action of the springs 44, into locking engagement for maintaining the closures 14 in a closed relation to the openings 13. The outer casing or housing 10 is provided with openings 46 in axial alignment with the bolts 40 to receive the terminals of the bolts after their passage through the keeper openings 45 in the closures 14. The means for moving the bolts against the action of the spring into locking engagement within the keeper openings 45,

consists of a pusher member 47 fulcrumed as at 48 to a bracket 49 on the standard 42, and a cam 50 secured to a transverse shaft 51 mounted for turning movement in the bracket 49. A lever 52 is secured to the shaft 51 for turning the same to cause the cams 50 to swing the pusher member 47 downwardly and effect the downward sliding movement of the bolts against the action of the springs 44. In order to positively maintain the bolts in their downward shifted position against the action of the springs 44, a latch 53 having a nose 54 is engageable with the lever 52, said latch being maintained by a spring 55 in a position to hold the nose 54 in its active position. The shaft 51 extends through the bearing 56 of a bracket 57 and has secured thereto at its extremity, a sprocket wheel 58.

Mounted on the outer end of the slide rod 35 for sliding movement therewith, is a frame 59, the side rails 60 of which are provided with semi-circular notches 61 at their lower ends, receiving and partially embracing a stationary bearing rod 62, which is secured to and projects outwardly from the frame of the machine. This bearing rod permits of sliding movement of the frame 59 with the slide rod, while permitting the slide rod to freely turn within the frame. The side rails are connected respectively at their upper and lower ends, by bolts and stays 63 and 64. The portion of the slide rod between the side rails of the frame 59, has secured thereto a sprocket 65. A sprocket chain section 66 is trained around and engages the sprocket 65 with its opposite terminals connected by connecting rods 67 with the terminals of a sprocket chain section 68 trained around and engaging the sprocket wheel 58 so that the sprockets 58 and 65 are operatively connected with each other. It will be noted, however, that the sprockets 58 and 65 are in a two-to-one ratio so that a quarter turn of the sprocket 58 will effect a half turn of the sprocket 65.

It will thus be noted that manipulation of the handle 52 to swing the same from the position illustrated in Fig. 2 to the position illustrated in Fig. 3, effects simultaneously the retraction and disengagement of the bolts 40 from the keeper openings 46 while the coupling bolt 39 is rotated in a direction with the slide rod 35 to disengage the same from the notch 34 in the head 33 of the rock arm 32.

In order to move the slide rod 35 and dispose the belt-shifting carriage 36 in a neutral position with the belts 26 and 27 on the loose pulleys 24 and 25, when the lever 52 releases the bolts 40 and disengages the coupling bolt, a connecting rod 69 is attached by a flexible chain section 70 at one end to the sprocket 58. The opposite end is connected by branch chain sections 71

to bracket arms 72 on the side rails 60 of the framework, the said chain section 71 being trained over a transverse guide 73 supported from the bearing rod 62 by a pair 5 of laterally spaced supporting arms 74. From this arrangement it will be noted that movement of the lever 52 from the position shown in Fig. 2 to the position shown in Fig. 3, effects a pull on the connecting rod 10 69, which in turn effects a pull on the branch chain section 71 which are trained around the supporting arms 74 whereby to draw the slide rod 35 and carriage 36 to a central neutral position where the belt-shifting 15 loops 37 and 38 dispose the belts wholly upon the loose pulleys 24 and 25.

From the foregoing it will be seen that a safety device has been devised in which starting of the machine is positively prevented except when the doors or closures 20 14 are in a closed relation to the doorway or opening 13, so as to allow the bolts 40 to be projected through the keeper openings 45. On the other hand, opening of the 25 doors 14 is prevented until the machine-driving mechanism has been shifted to a neutral position, by the release or retraction of the bolts 40 from the keeper openings 45. Damage to the machine is hence prevented due to the fact that closure of the 30 doorway 14 cannot be effected unless the inner hinged sections 12 are closed with respect to the drums or barrels 11.

What is claimed is:

1. In a washing machine including a stationary casing having a doorway, a closure therefor, a drum mounted in the casing for rotation, a reverse driving mechanism for the drum including a drive shaft operatively connected with the drum, a tight pulley secured to said drive shaft, a pair of loose pulleys mounted on the drive shaft at opposite sides of the tight pulley, oppositely driven belts respectively engaging the loose pulleys, slideable belt-shifting means for shifting the belts from the loose pulleys into engagement with the tight pulley to drive the shaft in opposite directions, a rock arm driven by one of the loose pulleys, a coupling device for connecting and disconnecting the rock arm with the belt-shifting means for actuating the same, a safety attachment for said machine, comprising an apertured portion in the casing closure, constituting a keeper, a locking bolt mounted on the casing, means for normally effecting the retraction and disengagement of the bolt from the keeper, and a common manipulating lever movable in one direction for simultaneously engaging the bolt with the keeper for locking the closure in closed relation to the doorway and for throwing the coupling device in engagement with the rock arm for rendering the driving mechanism active.

device in engagement with the rock arm for rendering the driving mechanism active.

2. In a washing machine including a stationary casing having a doorway, a closure therefor, a drum mounted in the casing for rotation, a reverse driving mechanism for the drum including a drive shaft operatively connected with the drum, a tight pulley secured to said drive shaft, a pair of loose pulleys mounted on the drive shaft at opposite sides of the tight pulley, oppositely driven belts respectively engaging the loose pulleys, slideable belt-shifting means for shifting the belts from the loose pulleys into engagement with the tight pulley to drive the shaft in opposite directions, a rock arm driven by one of the loose pulleys, a coupling device for connecting and disconnecting the rock arm with the belt-shifting means for actuating the same, a safety attachment for said machine comprising an apertured portion in the casing closure, constituting a keeper, a locking bolt mounted on the casing, means for normally effecting the retraction and disengagement of the bolt from the keeper, and a common manipulating lever movable in one direction for simultaneously engaging the bolt with the keeper for locking the closure in closed relation to the doorway and for throwing the coupling device in engagement with the rock arm for rendering the driving mechanism active.

3. The combination with a washing machine of the character set forth, of a safety attachment therefor comprising a keeper on the casing closure of the machine, a normally retracted locking bolt, a common manipulating lever movable in one direction for simultaneously engaging the bolt with the keeper to lock the closure in closed position and for throwing a coupling device into engagement with a rock arm for rendering the driving mechanism active, said lever when moved in the opposite direction permitting of the retraction and disengagement of the keeper and simultaneously disengaging the coupling device to render the driving mechanism inactive except when the closure is in fully closed position.

3. The combination with a washing machine of the character set forth, of a safety attachment therefor comprising a keeper on the casing closure of the machine, a normally retracted locking bolt, a common manipulating lever movable in one direction for simultaneously engaging the bolt with the keeper to lock the closure in closed position and for throwing a coupling device into engagement with a rock arm for rendering the driving mechanism active, said lever when moved in the opposite direction permitting of the retraction and disengagement of the keeper and simultaneously disengaging the coupling device to render the driving mechanism inactive, and means of connection between said manipulating lever and the slideable belt-shifting means for moving said means to a neutral position simultaneously with the manipulation of the lever to uncouple the coupling device and unlock the closure.

JOSEPH E. GARIGLIO.
